HENRY K. HESS, OF WOLCOTT, NEW YORK

SELF-SERVICE BOWLING ALLEY

Application filed October 20, 1930. Serial No. 489,982.

This invention relates to a self-service bowling alley involving the use of an outgoing runway along which the balls may be rolled by hand from one end to the other in the usual manner, and an underlying return runway along which the balls are automatically returned to a suitable pin-supporting platform at the receiving end of the upper runway so that the player may place the pins and cause them to be displaced by the returned ball at one and the same end of the alley.

The main object is to provide a self-service bowling alley of any desired length or width, standard or otherwise, in which the pin-supporting platform upon which the pins are placed is arranged at the serving end of the outgoing runway, and the served ball is automatically returned to said platform for displacing the stacked pins so that the individual player may serve the balls and pins from one and the same stand without the aid of other persons and thereby to greatly reduce the cost of operation of the plays.

One of the specific objects is to arrange the return runway directly under the outgoing runway from end to end thereof and to provide suitable deflectors at both ends of both runways whereby the served ball will be deflected downwardly from the delivery end of the outgoing runway, aided by the weight and momentum of the ball, onto and along the return runway and thence upwardly and forwardly by its momentum onto the pin-supporting platform for displacing the pins.

Another object is to provide the return runway with a power-driven impeller arranged directly under the delivery end of the outgoing runway for increasing the momentum of the ball in its course along the return runway sufficient to carry it onto and across the pin-supporting platform for displacing the pins.

A further object is to arrange the players stand and pin-supporting platform in approximately the same horizontal plane as the outgoing runway, with the players stand between the receiving end of the runway and platform, and also to provide the alley with a pocket or recess located between the plat-

form and players stand and below the upper surfaces thereof for receiving the returned balls and displaced pins so that the balls and pins may be conveniently accessible to the player on the stand for replaying and replacing respectively. 15

Another object is to provide a suitable stop for the displaced pins and returned balls located directly over the pocket or recess to cause the pins and balls to drop into the pocket following each play. 20

Other objects and uses relating to specific parts of the alley will be brought out in the following description.

In the drawings:— 65

Figure 1 is a perspective view of a self-service bowling alley embodying the various features of my invention.

Figure 2 is an enlarged longitudinal vertical sectional view of the same alley, partly broken away, taken in the plane of line 2—2, Figure 1. 70

Figures 3 and 4 are further enlarged transverse vertical sectional views taken respectively in the planes of lines 3—3 and 4—4, Figure 2. 75

Figure 5 is a perspective view similar to Figure 1, but considerably shorter, for home use, and having a slightly modified form of impeller for the return runway. 80

Figure 6 is an enlarged longitudinal vertical sectional view through the delivery end of the alley, shown in Figure 5, illustrating more clearly the modified form of impeller. 85

As illustrated in Figures 1 to 4 inclusive, this bowling alley comprises an elongated substantially rectangular frame —1— of box-like construction adapted to be supported in a substantially horizontal plane upon any suitable foundation for receiving and supporting an upper outgoing runway —2— and a lower return runway —3— underlying the upper runway —2— in vertically spaced relation thereto, to form an intervening passage for the balls upon their return from the delivery end of the upper runway —2—, in a manner presently described. 90

The outgoing runway —2— is provided with a substantially horizontal upper surface and may be of any standard dimensions com- 100

monly used in public alleys but obviously may be made of any suitable length or width, the opposite sides of the frame —1— being extended slightly above the surface of the upper runway —2— to form parallel guard rails —4— along the opposite longitudinal edges of the runway —2— to prevent lateral displacement of the balls therefrom.

The frame —1— is also provided with a player's stand —5— located at the serving end of the upper runway —2— and having its upper surface disposed in about the same horizontal plane as the upper surface of said runway.

The players stand —5— may be provided at one side with steps —6— leading from the floor of the building in which the alley is installed, to the surface of the platform which may be extended any distance beyond the opposite side of the alley to serve a similar purpose for other alleys which may be multiplied indefinitely side by side.

A platform —7— is built into the frame —1— to extend across and between the opposite side walls thereof some distance from the serving end of the upper runway —2— and also in longitudinally spaced relation to the players stand —5— with its upper surface disposed in substantially the same horizontal plane as the upper surface of the stand —5— and runway —2— for supporting the pins as —a—.

The portion of the frame —1— between the pin-supporting platform —7— and player's stand —5— is depressed below the upper surface thereof to form a pocket —9— for receiving displaced pins —a— and returned balls as —b—.

A stop bar —10— is mounted upon the frame —1— directly over the medial portion of the pocket —9— in spaced relation to the opposite end walls thereof to stop further progress of the ball and allow it to drop into the pocket —9— which also serves to receive the pins —a— as they are displaced from the platform —7— and at the same time permitting convenient access to the returned balls and displaced pins for repeating the play.

The distal end wall —11— of the frame —1— extends from the bottom of the frame upwardly across the adjacent ends of the runways —2— and —3— in spaced relation thereto and also some distance above the level of the upper surface of the runway —2—, and is provided on its inner side with a concave deflector —12— extending around the adjacent end of the upper runway —2— for deflecting the ball downwardly onto the underlying return runway aided by the weight and momentum of the ball.

Owing to the fact that the momentum of the ball, after leaving the end of the runway —2—, is somewhat retarded by contact with the deflector —12—, and particularly when the ball is moving more or less slowly

along the runway, it may be necessary to provide means for impelling the ball along the return runway with sufficient force and sufficiently greater speed than that of the ball to carry it to the pin-supporting platform —7— for displacing the pins thereon and for this purpose I have shown a power-driven impelling device consisting of an endless belt —13— mounted upon suitable drums —14— and —15— with its upper side disposed in a horizontal plane underlying the delivery end of the upper runway —2— in sufficiently spaced relation thereto to allow the ball to pass freely through the intervening space, one of the drums as —15— being operatively connected to an electric motor —M— or equivalent power device for moving the belt in the direction indicated by the arrows, Figure 2.

The impeller —13— is relatively short from end to end as compared with the length of the runways —2— and —3— and is preferably provided with a plurality of, in this instance two outwardly projecting V-shaped shoulders —16— of less radial depth than the distance between the upper side of the belt and lower side of the delivery end of the upper runway —2— so as to travel freely through the intervening space to serve as a means for positively driving the ball from the delivery end of the upper runway —2— into the stationary part of the lower runway —3—.

The belt —13—, including its radial shoulders —16—, may be made of rubber or equivalent resilient material to reduce to a minimum the noise incidental to the impact of the ball therewith and also to reduce the liability of slippage of the contacting surface between the ball and shoulders when contacting one with the other.

In some instances, however, the belt —13— may be replaced by a single drum —13'—, as shown in Figures 5 and 6, arranged directly over the delivery end of the upper runway —2— and provided with radial V-shaped shoulders —16— similar to those previously described, for driving the delivery ball —b— along the return runway —3—.

If necessary, the lower side of the delivery end of the upper runway —2— may be provided with a buffer —17— of rubber or equivalent material to assist in preventing rebound of the ball upwardly when engaged by the impeller —13— or —13'— and for more positively directing the return ball onto the stationary part of the return runway —3—.

The proximal end —18— of the frame —1— extends from the adjacent end of the lower runway —3— upwardly some distance above the horizontal plane of the upper surface of the pin-supporting platform —7— and is provided with a concave inner deflecting surface —19— extending from the upper surface of the adjacent end of the lower runway —3— around the adjacent end of and

above the platform —7— in sufficiently spaced relation thereto to allow the return ball to pass freely from the lower runway —3— onto the platform —7— for displacing the pins —a— 5 therefrom.

A cross bar —20— is mounted in the sides of the frame —1— closely adjacent the outer end of the platform —7— and in sufficiently spaced relation to the deflector —19— to allow 10 the ball to pass through the intervening space and to assist in guiding the ball from the adjacent end of the lower runway —3— onto the platform —7—.

The inner end face of the upper portion of 15 the end wall —11— overlying the delivery end of the upper runway —2— is substantially flat and perpendicular to the horizontal plane of said runway and is provided with a series of, in this instance five, targets —21—, 20 shown more clearly in Figures 1, 4 and 5, and consisting, in this instance, of the letters O A B C O, reading from the left-hand toward the right hand, Figure 4.

These targets face the player on the stand 25 —5— for easy visibility and indicate the relative positions of the pins —a— when the latter are properly placed upon the platform —7—, the center target —B— indicating the position of the center pin in the apex of the 30 triangle while the targets —A— and —C— indicate the positions of the outer walls between the apex and base of the triangle, the outer targets indicating the outermost balls in the base of the triangle.

35 Under this target system the player directs the ball along the runway —2— to a pre-selected target in the same manner as though the targets were pins, and relies upon the returning of the ball along the lower runway 40 —3— to the platform —7— to displace the pin or pins corresponding to the selected target.

In order that the ball may be returned along 45 the vertical plane of the selected target the lower runway —3— is provided with a series of, in this instance five, longitudinally extending parallel grooves —22— as shown more clearly in Figure 3, said grooves being arranged in the vertical planes of their corresponding targets —21— so that if the ball reaching the delivery end of the upper runway —2— is registered with any one of the targets —21—, it will be returned along the corresponding groove —22— of the lower runway —3— to the platform —7— for displacing the corresponding pin or pins.

Under these conditions each play directed 50 to any particular target will be as accurate in displacing the corresponding pin or pins as though the pins were placed in proper relation upon the distal end of the outgoing runway —2— in the usual manner.

As shown more clearly in Figure 2, the upper surface of the lower runway —3— is 55 slightly inclined downwardly from its proximal

end to its distal end to allow any ball which failed to be returned to the platform —7— to roll along the inclined runway toward the distal end thereof to be deposited in a pocket —23— which is preferably open 70 at one side to permit the removal of the ball for re-use if desired, without in any way interfering with the free operation of other balls along both runways.

Operation

The player on the stand —5— rolls the ball along the upper runway —2— to the distal end thereof where it is deflected downwardly into the underlying propeller section —13— or —13'— of the lower return runway —3—, said propeller being driven with sufficient speed to propel the ball along the remaining portions of the lower runway —3— and upturned deflector —19— onto the platform —7— for displacing the pins —a— therefrom, the further progress of the ball being checked by the stop bar —10— which causes it to drop into the pocket —9—, the latter also serving to receive the displaced pins 80 —a—.

It is, of course, obvious that at the beginning of a play the player will direct the ball toward one or the other, preferably the center target —B—, with the assurance that if properly directed it will be returned by the impeller —13— or —13'— along the corresponding groove —22— of the lower runway —3— and thence onto the platform —7— into engagement with the pin corresponding to the pre-selected target, thus completing the play, which may be repeated with the same or other balls according to the wishes of the player.

While I have shown the impellers —13— and —13'—, Figures 2 and 6, it is evident that these impellers might be omitted and the stationary part of the return runway —3— extended to or beyond the distal end of the upper runway.

The impeller section —13— or —13'—, Figures 2 and 6, may therefore be considered as parts of the lower runway —3— for the reason that they might remain stationary as desired, providing the ball is rolled along the upper runway with sufficient speed to cause it to return along the lower runway to the proximal end of the alley and onto the platform —7— for displacing the pins —a—.

This apparatus is particularly simple, practical and convenient for self-service playing in that the played balls are automatically returned to the platform —7— in close proximity to the players stand —5— and that the platform upon which the pins are placed is also in close proximity to the players stand, thereby avoiding the necessity for the services of pin boys or other persons.

What I claim is:

1. In a self-service bowling alley, an out-

going runway for the ball, a return runway for said ball underlying the outgoing runway, a platform at the proximal end of both runways for supporting the pins, means at the distal end of the outgoing runway for deflecting the ball downwardly therefrom, power-driven means underlying the distal end of the outgoing runway for receiving the ball from said means and propelling it along the return runway onto said platform for displacing the pins.

2. In a self-service bowling alley, an outgoing runway for the ball, a return runway for said ball underlying the outgoing runway, means for supporting the pins at proximal end of both runways, means for deflecting the ball downwardly from the distal end of the outgoing runway, means for projecting the ball along the lower runway, and means for deflecting the ball upwardly from the proximal end of the return runway onto the pin-supporting means for displacing the pins.

3. In a self-service bowling alley, an outgoing runway for the ball, a return runway for said ball underlying the outgoing runway, a pin-supporting platform at the proximal end of both runways, means for deflecting the ball downwardly from the distal end of the outgoing runway along the return runway, and means for projecting the ball along the return runway onto the pin-supporting platform for displacing the pins, and means between the platform and adjacent end of the outgoing runway for preventing the passage of the returned ball and displaced pins onto said outgoing runway.

4. In a self-service bowling alley, an outgoing runway for the ball, a return runway for said ball underlying the outgoing runway, a pin-supporting platform at the proximal end of both runways, a ball-stop between the platform and adjacent end of the upper runway, a ball and pin receptacle underlying the stop, an impeller underlying the distal end of the upper runway for driving the ball along the return runway, means for deflecting the ball from the delivery end of the upper runway into the path of said impeller, and means for deflecting the ball from the delivery end of the return runway onto said platform for displacing the pins.

5. In a bowling alley, an outgoing runway and an underlying return runway, means for directing the ball from the distal end of the outgoing runway onto the adjacent end of the return runway, a pin supporting platform at the proximal end of the outgoing runway, and a plurality of targets arranged horizontally spaced relation transversely of the bowling alley at the distal end thereof in line with the pins on the platform, said targets being visible to the player to enable said player to direct the ball along the upper runway toward any one of the preselected tar-

gets corresponding to the particular pin which it is desired to displace.

6. In a bowling alley, an outgoing runway and an underlying return runway, means for deflecting the ball from the distal end of the upper runway onto the adjacent end of the lower runway, a pin-supporting platform above the proximal end of the lower runway and in a plane below the upper runway, and means for deflecting the ball from the proximal end of the lower runway onto said platform for displacing the pins.

7. A bowling alley having an upper outgoing runway, a lower return runway, a pin-supporting platform at the proximal end of and in a plane below the upper runway, and means for deflecting the ball from the proximal end of the lower runway onto said platform for displacing the pins.

In witness whereof I have hereunto set my hand this 8th day of October, 1930.

HENRY K. HESS.
